CLAIM

The ornamental design for a controller panel, as shown and described.

DESCRIPTION

FIG. 1 is a front and upper left perspective view of a first embodiment of a controller panel showing our new design; FIG. 2 is a top elevational view thereof;

FIG. 3 is a right side elevational view thereof, the left side elevational view being a substantial mirror image thereof;

FIG. 4 is a rear and upper left perspective view thereof;

FIG. 5 is a bottom elevational view thereof;

FIG. 6 is a front and upper left perspective view of a second embodiment of a controller panel showing our new design; FIG. 7 is a top elevational view thereof;

FIG. 8 is a right side elevational view thereof, the left side elevational view being a substantial mirror image thereof;

FIG. 9 is a rear and upper left perspective view thereof; and FIG. 10 is a bottom elevational view thereof;

FIG. 11 is a front and upper left perspective view of a third embodiment of a controller panel showing our view design; FIG. 12 is a top elevational view thereof;

FIG. 13 is a right side elevational view thereof, the left side elevational view being a substantial mirror image thereof; FIG. 14 is a rear and upper left perspective view thereof; and, FIG. 15 is a bottom elevational view thereof.
